UNITED STATES PATENT OFFICE

AXEL G. W. WEDBERG, OF CHICAGO, ILLINOIS

MOLD FOR CONCRETE BUILDINGS

Application filed April 9, 1926. Serial No. 100,817.

My invention relates to improvements in the art of erecting monolithic structures of concrete or similar plastic materials, by which one story at a time including all exterior double walls, inside walls, partitions, ceiling slabs, and cornices are cast in a single pour forming one coherent mass. If it is desired, the walls and ceilings may be poured separately by following the features of my invention.

I propose to provide an improved molding apparatus including a base mold, wall forms used for exterior walls and inside partitions, insulating material for obtaining a dead air space in the exterior walls, and forms for ceiling cornices and ceiling slabs.

The forms include a series of panels of relatively small weight in comparison to area, which are reenforced by a plurality of detachable stiffening members, which members may be spaced to the different requirements so as to impart sufficient rigidity to the forms to withstand the pressure exerted against them when the concrete is being poured into the mold. The panels are locked together by simple and effective means operating to retain them in a flush and aligned relation, and providing for expeditious assembling of the forms when setting them up or taking them down.

The panels made in accordance with the features of my invention are of such a construction that they may be easily and cheaply assembled. Then, too, the panels are properly shaped and are reenforced to keep their molding surfaces flat and unwarped.

In accordance with other features of my invention, there is provided a novel base mold construction adapted to be associated with the wall panels. Means is provided for locking the base mold to the wall panels in such a manner as to maintain the lower ends of the wall panels in proper alignment. The base mold is so constructed that after the concrete has been poured and set, it may be with facility removed from the molding structure, allowing the bottom of the wall panels to be swung away from the finished concrete walls. That is to say, the base mold is first removed in order to permit access

with facility to the wall panels. After the removal of the base mold the wall panels may be lowered from a normal position and thereafter removed from the walls.

The invention also provides for locking means between the ceiling panels and the wall panels, whereby removal of the wall panels after the hardening of the concrete is greatly facilitated without, at the same time, necessitating the removal of the ceiling panels.

The wall forms of my invention are preferably held together at top and bottom by steel bands passing under the base at the bottom and between the panels and cornice molds at the top.

Further objects and advantages of my invention will more fully appear from the following detailed description taken in connection with the accompanying drawings which illustrate several embodiments thereof, and in which:

Figure 1 is a vertical sectional view taken through the concrete form of my invention, the section being taken on the line 1—1 of Figure 2;

- Fig. 34 is a modification of my invention, 70 illustrating how two of the panels, such as those shown in Fig. 32, may be positioned one upon another and interconnected to provide a relatively high single concrete wall construction;
- Fig. 35 is a sectional view taken substantially on the line 35—35 of Fig. 34 looking in the direction indicated by the arrows;
- 75 Fig. 36 is a view of a modified form of panel embodying the features of my invention adapted to be used independently of the detachable stiffening members;
- Fig. 37 is a sectional view taken substantially on the line 37—37 of Fig. 36, looking upwardly;
- 80 Fig. 38 is a substantially vertical section taken on the line 38—38 of Fig. 36, looking in the direction indicated by the arrows;
- Fig. 39 is a sectional view taken on the line 39—39 of Fig. 36;
- 85 Fig. 40 is a sectional view taken substantially on the line 40—40 of Fig. 36; and
- Fig. 41, referring to Sheet 2 of the drawings, is a vertical section taken on the line 41—41 of Fig. 3.
- 90 Referring now to the drawings in detail, in which like reference numerals designate similar parts throughout the several views, I have illustrated somewhat fragmentarily in Figure 1 a molding construction embodying the features of my invention positioned upon a previously molded story. As was previously mentioned, my invention relates to the art of molding one story upon another in building structures. Now, first, I shall describe in detail the base molds of my construction designated generally by the reference character 10, and best illustrated in Figs. 3, 4, 5 and 7. The base molds 10 are preferably positioned upon a concrete slab or the ceiling slabs of the under story. This will be obvious from the illustration in Figure 1.
- 95 The base mold comprises essentially a plurality of interchangeable units, which units are interconnected by mechanism embodying features of my invention. Each base mold unit comprises a vertical wall 11 and an angular steel member 12. The wall 11 is provided with a molding surface 13 against which the concrete is set. The wall member 11 and the angular member 12 may, if it is so desired, be formed integral. I preferably make the wall member of wood and the angular member 12 of steel and thereafter connect them by suitable fastening means. The member 12 comprises a shoe portion 14 having a laterally offset portion 15 extending substantially vertically therefrom. The angular member 12 also has a leg 16 which abuts the rear face of the molding wall 11. The leg 16 is fastened to the wall 11. The upper part of the wall 11 is provided with an inclined surface 17 which co-operates with an edge 18 of the leg 16 to form a seat for a wall panel adapted to be superimposed thereon. The inclined surface 17 extends upwardly until it meets the 100
- 105
- 110
- 115
- 120
- 125
- 130

edge 18 of the leg 16 associated with the rear face of the member 11.

One end of each unit 10 has fastened there-to an extension plate 20. The plate may, if it is so desired, be welded to the leg 16 of the angular member 12. As best shown in Fig. 4, the plate 20 is equipped with a slot 21 reduced at one end as indicated at 22. Now the other end of the unit 10 is provided with a 10 pair of guide pins 23, preferably secured to the leg 16 of the member 12 (Fig. 5). These pins 23 extend from the rear surface of the unit 10 and are adapted to fit in apertures 24 in the extension plate 20 (Fig. 4). I desire it 15 understood that although I have illustrated the units 10 in Fig. 3 as being at right angles with respect to each other it is, of course, obvious that the units may be positioned in alignment with the pins 23 of the end of one 20 unit positioned within the apertures 24 of the plate associated with the end of the abutting unit. Thus it will be seen that the units may be interconnected in an aligned position.

In Fig. 3 I have illustrated the units 10 as 25 being connected to a corner base member, designated generally by the reference character 25. This member 25 comprises an angular cast iron member 26 adapted to be aligned with the walls 11 of the adjacent units 10. 30 That is to say, the outer faces of the member 25 are adapted to be aligned with the molding faces of the units 10 to present a perfectly flush outer molding surface to the concrete being poured.

Secured to the angular member 26 by a bolt 27 is a plate 28 (Fig. 5) having a pair of apertures 29 for receiving the pins 23 of the associated end of the mold member 10. The plate 28 is equipped with an aperture 30 40 through which the shank of a screw 31 is threaded into the member 26. The screw 31 may be removed to permit of the moving of the plate 28 to the position illustrated in dotted lines in Figure 5. The plate 28 is 45 equipped with a slot or opening 34 having a reduced portion 35. This slot 34 communicates with a pocket 36 in the member 11 of the corresponding adjacent end of the associated molding unit 10 through an opening (Fig. 4) 50 37 in the associated leg 16 of the shoe 12. The opening 37 in the rear of the unit 10 is preferably of the same shape as the slot 34.

It should be also noted that the member 26 is provided with a pocket or opening 40 55 which communicates with a slot 41 in the extension plate 20. The slot 41 has a reduced portion 42. Also, the slot 41 is adapted to co-operate with a similar slot 43 formed in the member 26 which communicates with the 60 pocket or opening 40. Now, as will be readily obvious from the illustrations in Figures 3, 4 and 5, the free ends of the plates 20 and 28 are secured to the adjacent and co-operating apertured parts by means of wedges 45. 65 The wedges are all of the same construction

and I preferably associate two of the wedges with each plate. I have illustrated the wedge in perspective in Figure 18 of my drawing. I shall now describe this wedge in detail. The wedge 45 comprises a body portion 46 70 and a pair of lateral ears 47 and 48 which extend in opposite directions and which constitute the head of the wedge. The wedge is tapered in construction and has a pair of openings 49 and 50 adapted to receive other similar wedges. Each wedge is also provided with a lateral projection 51, the purpose of which will be more fully described herein-after in connection with the various uses of my novel general utility wedge. 75

Now referring again to Figure 3, it will be obvious that the head of the wedge 45 is adapted to be inserted through the co-operating slot in the plate 20 and the member 26 and into the pocket 40 of the member. 80 By sliding the wedge over to a position in rear of the reduced portion 42 of the slot, the lateral ears 47 and 48 of the wedge 45 will engage the wall of the pocket 36 and thus be maintained in a given position. 85 Then, another wedge 45 may be pushed in the slot 50 of the other wedge 45, which second wedge will serve to cause the extension of the plate 20 to tightly engage the outer wall of the member 26, thus binding the units 90 10 to the wall 26.

The plate 28 may be secured to the associated unit 10 by a pair of wedges 45 in much the same manner as the extension of the plate 20 is secured to the member 26. The 100 pair of co-operating wedges will serve to cause the plate 28 to tightly engage the outer wall of the associated unit 10. It will be apparent, therefore, that by using the above described construction the units 10 may be 105 tightly connected to the corner member 26. Also, by removing the screw 31, as previously described, the plate 28 may be swung to the dotted position illustrated in Figure 5 when the associated wedges 45 are removed therefrom. This permits of the ready disconnection of the units from the corner piece 26 110 after the cement has set.

Referring now to Figure 7 it will be observed that a panel for molding the walls of a house is adapted to rest upon the inclined edge 17 of the base mold 10. I have designated the panel by the reference numeral 60 and shall now proceed to describe the panel in detail. The panel 60 (Figure 20) 115 comprises essentially a sheet metal front base 61 having mounted thereon a plurality of wooden cleats or slats 62. The lower edge of the sheet metal base 61 is formed into a bent portion 64 which is bent back upon the area enclosed by the sheet 61 and is preferably fastened to the cleats 62. By referring to Figure 7 it will be noted that the bent portion 64 is bent to accommodate the inclined edge 17 of the bottom mold 10. That 120 125 130

is to say, the bent portion 64 of the sheet 61 is bent so that it will seat on the inclined edge 17 of the bottom mold. I have indicated the inclined portion of the portion 64 by the reference character 66. Then, too, the portion 64 is bent into an upwardly extending portion 67 which abuts the edge 18 of the angular member 12. This extension 67 may be reenforced by a plate 68. As illustrated in Figure 20, the portion 67 of the flange 64 is equipped with a plurality of slots 68' similar to the slots 34 and 41 previously described. These slots are adapted to receive the heads of wedges 45 in much the same manner as the slots 34 and 41 receive the wedges. Each of the wedges 45 when mounted in the aperture 68' extend outwardly from the panel 60 (Fig. 7) and are adapted to have inserted through the opening 50 thereof another wedge 45 which serves to maintain the panel 60 in alignment with the bottom mold 10. Also, these wedges 45 serve to prevent the panel 60 from becoming dislocated with respect to the bottom mold 10.

Now referring again to Figure 20, it will be noted that the top edge of the sheet 61 is bent back upon itself, as indicated at 70, forming a strip 71 which is suitably fastened to the cleats 62. Now the upper part of the turn back portion 70 is equipped with a longitudinal groove 73, as best illustrated in Figures 20, 21 and 8. The purpose of this groove will be more fully explained in conjunction with my novel ceiling cornices which will be described hereinafter.

Each of the sides of the panel 60 illustrated in Figure 20 are formed identically the same. Therefore, it is believed the description of one side will suffice for both. Each side of the panel is formed so that a portion of the sheet 61 overlaps the cleats 62, as indicated at 75. Formed integral with this overlapping portion 75 is a lateral extension 76 which includes a hook portion 77 and a reenforcing rib 78 (Figure 12). Also, as best shown in Figure 12, the molding panel 60 is connected to the overlapping portion 75 by means of a lateral extension 74 formed integral with the sheet 61. The reenforcing rib 78 is secured to the cleats 62 by means of nails 79. Now, when the panels are positioned edge to edge, as illustrated in Figure 12, the hooks 77 of the adjacent panels are adapted to co-operate with my novel clamping means to insure of a rigid connection between the adjacent panels. Also, these clamping hooks 77 enable the proper alignment of the panels, as will be more fully explained hereinafter.

It will be noted from the illustration in Figure 20 that the cleats 62 are disposed in the slanting position. This slanting of the cleats enables the cleats to be used as wedges for urging the edges of the panel outwardly. That is to say, the cleats are pushed down, one upon another, under the turn back por-

tion 75, with their ends in engagement with the side edges of the panel. These slanting cleats serve to prevent buckling or bending of the panel in a longitudinal direction. They also insure a perfectly true molding 70 surface on the front face of the panel.

I have illustrated the clamping means in detail in Figure 12. This device is designated generally by the reference character 80. It comprises essentially a pair of clamping jaws 81 and 82 adapted to engage with the hook portions 77 on the associated edges of the panel 60. The clamping jaws 81 and 82 are identical in construction. A detail view of one of the jaws is illustrated in Figure 15. The jaw comprises a hook portion 83 for engagement with the hook portion 77. Also, each jaw is provided with three openings 84, 85 and 86. The opening 84 is preferably circular in form and the opening 85 is preferably irregular in shape. The aperture 86 is rectangular in formation and is adapted to accommodate one of the wedges 45. Now the clamping jaws 81 and 82 are adapted to be associated with each other in such a manner that their various openings register. A wedge 45 is then inserted in the openings 86 of the two jaws and serves to tie the jaws together. Associated with the jaws is a guide element 88 (Figure 14) having a slot 89 and a pair of apertures 90 and 91 adapted to be associated with the apertures 85 and 86 of the clamping jaws. The aperture 91 is circular in shape and the aperture 90 is somewhat larger than the aperture 91. The slot 89 is adapted to accommodate a wedge 45, the purpose of which will be more fully explained hereinafter. Then, too, the two jaws and the element 88 are adapted to be secured together by means of a pair of bolts 93 and 94. The bolts 93 and 94 are each provided with a nut 95 (Figure 13). The openings 85 are somewhat larger than the shank of the associated bolt 94 and the opening 90 in the guide element 88 is larger than the shank of the bolt 93. Thus it will be seen that I have provided a lost motion connection between the jaws 81 and 82 and the guide element 88.

Associated with the guide element 88 is what I preferably term a stiffener 100. Referring to Fig. 10 it will be noted that the stiffener 100 comprises a longitudinal T iron 101 provided with a trussed construction consisting of an L iron 102 and side plates 103 which connect the two irons 101 and 102. The L iron 102 has its ends bent inwardly towards the T iron 101 to which the ends are fastened, as indicated at 104. The ends of the stiffener are each provided with a lateral projection comprising a T iron 105 (Figure 11). The purpose of this T iron 105 will be explained hereinafter.

Now, as illustrated in Figure 12, the base of the T iron 101 is adapted to be placed perfectly flush with the inner edges of the join-

ing panels 60. The projecting leg of the T iron 101 enters the slot 89 in the guide element 88. The wedge in the slot 89 serves to urge the T iron 101 towards the adjoining panel 60 and also serves to urge the guide element and clamping jaws 81 and 82 outwardly. This results in the hooks 83 drawing the hook portions 77 away from the associated panel 60. Also, the clamping jaws 10 are urged towards each other by means of the wedge 45 which serves to pivot these jaws inwardly. Once the wedges 45 are in position in my novel clamping device 80, a screw 106 is threaded into an aperture 107 in the guide element 88 until its end abuts the associated portion of the T iron 101. This screw in reality constitutes a set screw for preventing the clamping device 80 from sliding along the T iron. Now it will be obvious that the 20 clamping device 80 is guided in its action by the T iron 101 of the stiffener 100. Also, it will be apparent that the device serves to at all times maintain the stiffener in tight engagement with the rear edges of my novel 25 molding panels 60.

The T iron 101 of the stiffener 100 (Figure 7), referring more particularly to the lower end of the stiffener, is adapted to set in the shoe member associated with the base mold. 30 The flange of the T iron 105 is adapted to abut the lateral extension 15 of the shoe 14. Then, too, the base of the T iron 101 abuts the other leg 16 of the angular element 12. Thus it will be seen that the lower part of 35 the stiffener 100 completely occupies the space separating the vertical leg of the angular element 12 and the extension 15. Obviously, any stresses imposed upon the stiffener 100 will be transmitted through the iron 105 to 40 the shoe 14, and more particularly to the lateral extension 15. As previously described, the panels 60 are adapted to rest upon the slanting edges 17 of the base mold 10. Also the panels at the corners of the structure being molded are adapted to rest upon the slanting edges 17' of the associated corner base molds 25. The panels at the corners also abut at their rear edge an upwardly extending projection 18' on the base mold 25 (Figure 50 6).

In Figure 1, I have illustrated a substantially complete molding device embodying the features of my invention. The base molds 10 are positioned upon the previously molded structure designated generally by the reference character 110. That is to say, after one story of a given structure has been molded, such as the story 110, the molding 60 panels and devices are removed from the mold after it is set and are again set up in position upon the finished story ready to receive another pouring of cement. In Figure 1, I have also designated generally by the 65 reference character 111 a part of a scaffold

device which may be of any usual or conventional configuration.

In practice the base molds are first placed upon the structure 110 and the molding panels are then positioned on the slanting edges of the base molds. Thereafter, the stiffeners are associated with the molding panels. Also, the lower end of the stiffeners are disposed in the corresponding shoes, as previously described. Now in order to maintain the stiffeners in position until the cornice molds are in place, I preferably provide each stiffener with a resilient device such as that illustrated in detail in Figures 29 and 30. The device consists simply of a spike 112 driven into a cleat 62 of the panel and a spring 113 surrounding the shank of the spike having one edge disposed over an edge of the cleat 62. The other end 114 of the spring is provided with a hook-like portion adapted to 80 co-operate with the T 101 of the stiffener to hold the same in position until the upper end of the T is set in a suitable shoe associated with the ceiling cornice. When the end 114 is in this shoe it will, of course, be 90 in the position indicated by dotted lines in Figure 30.

In Figure 1 I have illustrated a pair of spaced panels 60 which define a wall of the structure to be poured. Positioned intermediate the spaced panels 60 is a hollow wooden core member 115 which is adapted to define a dead air pocket in the wall being poured. As is well known to those familiar with the molding art, this pocket serves as a heat insulator in addition to serving to prevent the accumulation of dampness. Extending through this core member 115 are a plurality of iron reinforcing elements 116 which serve to tie the cement on opposite sides of the core member 115 together. 100

As best shown in Figure 2, the panels 60 may be connected at the corners by means of wooden corner pieces, such as the pieces indicated by the reference numerals 120 and 121. 110 The associated panel 60 may be tightly clamped to these corner pieces by any suitable clamping mechanism, such as the clamping device designated generally by the reference character 122. This device includes a pair of jaws 123 and a wedge 124 for interconnecting the jaws. The wedge 124 may be of the same general type as the wedge 45. Of course, it is to be understood that the corner pieces 120 and 121 are associated with the 120 base corner molds 25.

Referring again to the base mold 10, it will be observed that the shoes associated with the opposite panels, are tied together by means of steel bands 125. Each of these bands is disposed immediately under the base mold and the core member 115 (Figure 1) and has one end formed into a lateral extension 126 equipped with a hook portion 127 adapted to fit over the lateral extension 15 130

of the associated shoe 14. The other end of each band is equipped with a device such as that illustrated in Figure 41. I have designated this device generally by the reference character 128. This device is adapted to abut the extension 15 of the shoe 14. That is to say, one end of the band 125 has a portion for hooking over a portion of one shoe, and the other end of the band has a device 128 adapted to co-operate with the extension 15 of the opposite shoe. Thus the two molding walls or panels are tied together against lateral expansion.

The device 128 comprises a member 129 having a recess in its lower portion 130 for accommodating the band 125 and being equipped with a plurality of projections 131 for fitting in corresponding apertures in the band 125. In practice, the projections 131 of the member 129 are first inserted into the corresponding apertures in the end of the band 125 and then the member 129 is placed in a position adjacent the associated edge of the shoe (Figure 5). The member 129 is provided with a clamping plate 135 having a slanting edge 136 for engaging a corresponding edge on the strip of material 125. The plate 135 is preferably secured to the member 129 by means of bolts and nuts 137. Also, the plate 135 is adapted to be tightened in place by means of a screw 140 threaded into the member 129. It will thus be apparent that I have provided an excellent device adapted to abut the corresponding shoe and to tightly maintain in place the corresponding end of the band of material associated therewith. The tie bands 125 are adapted to take up the stresses imposed upon the shoe members by the stiffeners 100. As previously explained, the stiffeners 100 are adapted to receive the stresses and strains imposed upon the panels by the concrete when it is being molded.

As previously described, the upper end of each panel 60 is equipped with a continuous longitudinal groove 73. It should also be noted (Figure 20) that the upper end of the panel is provided with a plurality of depressions 74 for receiving the bands which will be described hereinafter. As shown in Figure 1, a plurality of tie bands extend across the upper ends of the associated panels 60. I have designated this band generally by the reference character 141. The band 141 has a tongue portion 142 adapted to fit in the longitudinal groove 73 in the corresponding panel. Each band 141 has two of these tongues. I have indicated one of these tongues by the reference character 142 and the other by the reference character 142'. It should be understood that each of the bands 141 will lie in a recess 74' in the associated panel 60.

Referring to Figure 8, it will be noted that each end of the band 141 is equipped with an aperture 144 for receiving any suitable wedge 145. Associated with this wedge 145 is a cor-

nice member 150, which will be described hereinafter.

Mounted upon the top of the outer panel 60 is a top mold member 146 (Figure 19) which comprises a sheet metal molding wall 147 having a lateral extension 148 extending outwardly from the panel. This extension 148 has a lateral projection 149 adapted to co-operate with the T iron 105 of the associated stiffener 100. The extension 148 is provided with a plurality of apertures 149' through which wedges 151 are inserted (Figure 1). The wedges 151 are adapted to extend through corresponding openings in the associated tie bands 141 to tie the bands to the top mold member 146. The top mold member 146 has its extension 148 formed with a longitudinal tongue 153 adapted to be inserted in the corresponding groove 73 of wall panel 60. Thus it will be seen that the top mold member 146 is utilized to maintain the tongue 142 of the band 141 in place in the longitudinal groove of the associated panel.

The cornice member 150 is illustrated in perspective in Figure 16. This member is preferably made of sheet metal and comprises an arcuate shaped portion 160 having formed integral therewith a substantially flat portion 161 adapted to normally be disposed in a horizontal plane. The portion 161 has a portion 162 turned back upon itself forming a lateral extension 163. This lateral extension 163 is adapted to extend over the edge of the T iron 105 (Figure 8). As best shown in Figure 8, the extension 161 and the lateral projection 163 in reality constitute a shoe for receiving the end of the stiffener 100. The stresses imposed upon the stiffener 100 are adapted to be transmitted through the T 105 to the lateral extension 163 of the cornice member 150.

The horizontal extension 161 of the cornice member 150 is equipped with a plurality of square openings 170 for receiving the previously described wedges 145. The lower ends of these wedges (Figure 8) are adapted to abut the upper end of the rear face of the associated panel 60. These wedges prevent the bands 141 from slipping out of place. The extension 161 is also equipped with a plurality of apertures 172 through each of which one jaw 173 of a clamping device 174 is adapted to be inserted (Figure 8). The clamping device 174 serves to tie the cornice piece 150 to the associated panel 60. The lower end of the jaw 173 is pivotally attached to another jaw member 176 having a portion adapted to engage the under edge of one of the slats 62 in the panel 60. I have designated this jaw portion by the reference numeral 175. The member 176 (Figure 9) has a portion 176' turned back upon itself to form a pocket for receiving one of my novel wedges 45. The member 176 and the portion 176' are attached to the end of the jaw member 173 by means of a pivot bolt and nut construction 177. The

side of the jaw 173 is equipped with a plurality of corrugations 178 against which the upper edge of the wedge is adapted to abut. Now once the wedge 45 is in place in the pocket formed by the member 176, the upper edge of the wedge will tightly abut the corrugations 178 which will serve to prevent upward displacement of the wedge. By forcing the wedge in position, both of the jaws, due to the pivotal mounting, will be drawn together thus causing the cornice mold 150 to be drawn into a tight engagement with the upper end of the molding panel 60. This clamping device may be used in many other analogous capacities in the molding art construction. For example, I have provided the mold member 146 (Figure 19) with a plurality of apertures 153' through each of which a jaw 173 may be inserted to clamp the member 146 to the associated panel 60 in the same manner as described in connection with the construction illustrated in Figure 8.

The cornice mold 150 is also provided with a lateral edge 180 (Figures 8 and 16) having a right angle portion 181 bent back over itself. This portion 181 forms a pocket for a purpose to be hereinafter described. The portion 181 includes a hook portion 182 which is adapted to be used in conjunction with a clamping device. Each of the pockets 181 are adapted to receive an edge of a longitudinal wooden beam 185, such as the beam illustrated in Figure 1. These beams will each be secured to the cornice member 150 by means of a clamping band 186 having its ends formed into hook portions 187 for tying the hooks 182 of the adjacent cornice members together. A wedge 188 may be inserted intermediate the band 186 and the beam 185. Now the beams 185 are adapted to support ceiling panels 200, which will now be described.

Referring to Figures 24 to 28, inclusive, it will be noted that each panel comprises a sheet metal molding surface 201 reenforced by a plurality of wooden cleats 202. In construction the panels 200 may be much the same as the panels 60. The corner of each panel 200 is equipped with a small corner piece of metal 203 (Fig. 28) having an aperture 204 for receiving a nail, screw, or the like. The edge of each panel is provided at its rear face with a hook portion 206, such as the portion 77 described in connection with my molding panels 60. The portions 206 of adjoining panels are adapted to form a pocket for receiving one of the wooden beams 185.

The hook portions 206 of the ceiling panels 200 may be secured together by means of a clamping band 186. A wedge 188 may be inserted between the band 186 and the beams 185. The corners of the panels 200 are secured to the beams by means of nails 210 extending through the apertures 204.

Now from the foregoing description it will be obvious that I have provided a readily demountable molding construction for molding an entire story of a building at one time. My invention, however, is not to be limited by the detailed disclosure which I have made, but only insofar as defined by the claims attached hereto.

Referring to Figures 31, 32 and 33, I have illustrated a modification of my invention. In this form of the invention the same stiffeners 100 and panels 60 may be employed in the molding construction. The difference between this construction and that disclosed in Figure 1 lies in the form of the shoes associated with the ends of the stiffeners 100. Since both the panels and the stiffeners are the same as that already described in detail, it is believed that it will not be necessary to redescribe these parts. Associated with the lower end of each of the stiffeners 100 is a wooden shoe member 215 having an upward projection 216 which defines a pocket for receiving the T 105 of the end of the stiffener 100. The lower end of the panel 60 is adapted to rest upon the wooden shoe 215. The shoes of the adjacent panels are tied together by means of tie bands 217. One end of the tie band 217 is provided with a lateral extension 218 and a nail 219. This lateral projection 218 abuts the side of the wooden shoe 215.

The other end of the tie band 217 may be secured to a device such as that illustrated in detail in Figure 41. I have designated this device in Figure 32 generally by the reference character 128'. This device is adapted to abut the outer edge of the shoe 215 and to tie the two shoes together.

The upper ends of the panels 60 are provided with a pair of shoes 215' substantially the same as the wooden shoes 215. These shoes 215' are tied together by means of tie bands 217'. Each of these bands has a lateral extension 221 adapted to be fastened to the edge of one shoe, and a lateral extension 222 adapted to be fastened to an edge of another shoe. The extension 222 is also provided with an inwardly extending hook-like portion 223 adapted to fit over the base of the T iron 105 of the associated stiffener 100.

Obviously, the stresses imposed upon the stiffener 100 will be transmitted through the T iron 105 to the shoe associated therewith. The shoe in turn will transmit the stresses to the tie band. It will be noted that the projection 216 of the shoe in reality constitutes a shoulder against which the T iron 105 abuts. It is this shoulder that takes the stresses imposed upon the stiffener.

In Figures 34 and 35 I have illustrated still another modification of my invention. In this form of the invention the same panels 60 or 200 are employed as were used in my first modification of the invention. The

panels 60, however, in this construction are positioned one upon another. In other words, this construction is adapted to be used where it is desired to build a relatively high wall. 5 The panels, however, in this form of the invention are reenforced by wooden beams 230. The beams 230 are tied to the panels by means of a suitable clamping band 231 in much the same manner as the band 186 was tied to the hook portions 206 of the ceiling panel 200. 10

Extending between the panels 60 is a plurality of tie bands 232. The ends of the tie bands 232 are adapted to be secured to a transverse beam 233 associated with the longitudinal stiffener beam 230. The tie bands 232 will serve to tie the panels together intermediate the ends of the wall, so as to reinforce the panels at this point. Each of the bands 232 is equipped with a lateral extension 20 adapted to co-operate with the longitudinal beam 233. I have indicated this extension by reference character 234. Nails 235 may be used to fasten the band 232 to the beam 233.

Now it is apparent that when it is desired 25 to pour a relatively high wall, it is necessary to employ two or more panels, one upon another. The panels should be reinforced intermediate their ends by tie bands, such as the bands 232. I have found the arrangement illustrated in Figures 34 and 35 an ideal 30 one, as far as a relatively high wall is concerned.

In Figures 36 to 40, inclusive, I have illustrated a modified form of molding panel. 35 This form of the panel is inherently stiff and hence does not require any stiffeners 100. This form of panel is ideal for molding foundations and the like in a given building construction.

40 Each panel comprises a sheet metal molding surface 250 having its edges formed into a lateral extension 251 which defines the edges of the panel. Formed integral with the extension 251 is a right angle portion comprising a pair of legs 252 and 253. The legs 252 and 253 are disposed at right angles to each other. The leg 252 co-operates with the edge or lateral extension 251 to form a pocket for receiving a plurality of wooden 45 cleats 254. The cleats 254 may be disposed in a slanting position and wedged in place in much the same manner as was the case with the cleats 62 in my panel 60.

It should be noted, as best shown in Figure 36, that only the sides of the panel are formed with the angular portions previously described. The ends of the panel are each provided with a lateral extension 256 adapted to accommodate transverse wooden bars 257'. 55 Each of the angular portions comprising the legs 252 and 253 are adapted to receive longitudinal stiffening wooden bars 257. The bars 257', together with the bars 257, define the periphery of the panel as far as its rear 60 face is concerned.

The angular portions are preferably secured to the cleats 254 by means of nails hammered into the cleats at a diagonal angle. I have indicated the nails generally by the reference character 258 (Figure 39). The legs 70 253 of the angular portion are fastened to the corresponding wooden stiffening bars 277 by means of nails 259. Also, the reenforcing bars 257 are fastened to the cleats 254 by means of angular nail elements 260. Each of the nail elements 260 includes (Figure 40) a pair of nail portions 261 and 262 disposed at right angles to each other and connected to a common connecting link 263. The connecting link 263 extends across the width of the leg 253 of the angular portion and is adapted to tightly hold it against the corresponding wooden stiffening bars 257.

The wooden bars 257 and 257' are in turn interconnected by a plurality of wooden bars 85 265 fastened to the rear of the cleats 254. These wooden bars 265 serve to reinforce the wooden bars 257 and 257' and to stiffen the panels.

I claim:

1. In a molding construction, a base mold including a lateral shoe, a molding panel supported by the said base mold, a stiffener for the said molding panel, said stiffener having a portion associated with the said shoe, and means connecting the said portion of the stiffener with the shoe for resisting lateral movement of the stiffener and for causing the stresses to be transferred to the base mold.

2. In a molding construction, a base mold, a molding panel supported thereon, a shoe associated with the said base mold, a stiffener for the molding panel having its lower portion set in the said shoe, and means connected to the lower portion of the stiffener adapted to co-operate with the shoe and the base mold to prevent twisting of the stiffener.

3. In a molding construction, a plurality of unitary base molds, each having one end equipped with a lateral extension and its other end with a pocket, the lateral extension of one unit being adapted to co-operate with the pocket of the adjacent unit to interconnect the unitary base molds, and detachable means cooperating with said extension and projecting into said pocket and exerting a wedging effect for securing the mold sections together.

4. In a molding construction, a plurality of base molds, each of the said base molds having one end equipped with a lateral extension and its other end with a pocket, the said extension having an opening of a predetermined form and the said pocket having a corresponding opening adapted to co-operate with the opening in the extension, the lateral extension of one base mold being adapted to co-operate with the pocket of the adjacent base mold.

5. In a molding construction, a plurality of base molds, each of the said base molds having a lateral extension associated with one end and a pocket associated with the other end, the extension of one base mold being adapted to co-operate with the pocket of the adjacent base mold, the pocket end of each base mold being equipped with a pin adapted to co-operate with the extension of the adjacent base mold to properly locate the said extension.
6. In a molding construction, a plurality of base molds, each of the said base molds having an extension associated with one end and a pocket associated with the other end, the pocket end of each base mold being provided with a plurality of guide pins adapted to co-operate with the extension of the adjacent base molds to tie the adjoining base molds together and to properly align the extension plates.
7. In a molding construction, a plurality of base molds, each of the said base molds having an extension associated with one end and a pocket associated with the other end, the extension of one base mold being adapted to co-operate with the pocket of the adjacent base mold to interconnect the base molds, and a wedge construction for forcing the extension of one base mold into a relatively tight engagement with the rear face of the adjoining and co-operating base mold.
8. In a molding construction, a plurality of base molds, each of the base molds having an extension piece associated with one end thereof and a pocket associated with the other end thereof, the extension of one base mold being adapted to co-operate with the pocket of the adjacent base mold to interconnect the base molds, the said extension plate being pivotally attached to its associated base mold to permit of its being moved clear of the adjoining base mold to disconnect the adjoining mold.
9. In a molding panel construction, a molding surface comprising a sheet of metallic material having an edge bent into a hook and having a portion doubled back upon the said hook to form a brace for strengthening the hook and for preventing lateral movement thereof.
10. A molding panel comprising a molding surface consisting of a sheet of metallic material having an edge thereof bent into a hook construction and having a portion doubled back on the said hook construction and extending laterally therefrom to reinforce the hook and to resist lateral movement of the hook, the said hook forming a pocket with the rear face of the panel.
11. A molding panel comprising a molding surface of sheet material having an edge thereof formed into a lateral extension projecting from the rear face of the panel and equipped with a portion bent back upon it self and at an angle to the extension to reinforce the extension and to reinforce the panel itself.
12. A molding panel comprising a molding surface consisting of a sheet of metallic material having its edges bent back upon itself to form pockets for receiving a plurality of cleats, and a plurality of cleats positioned in the said pockets and constituting the rear of the panel, the said cleats being disposed in a slanting position so as to wedge the sides of the panel outwardly and to thus stiffen the sheet of metallic material against distortion.
13. In a panel construction, a pair of abutting panels disposed edge to edge, each of the said panels having its edge formed into an extension extending laterally from the rear face of the panel, the said extension being adapted to co-operate with the extension of the adjoining panel to form a pocket, and a supporting beam disposed in the pocket to which the edges of the panels are fastened.
14. In a ceiling panel construction, a pair of abutting panels disposed edge to edge, each of the said panels having its edge formed into an extension forming a hook extending laterally from the rear face of the panel, the said extension being adapted to co-operate with the extension of the adjoining panel to form a pocket, a supporting beam disposed in the pocket to which the edges of the panels are adapted to be fastened, and fastening means including a band of resilient material for straddling the beam and for interconnecting the hooks to draw the edges of the panels downwardly and tightly against the beam.
15. In a ceiling panel construction, a pair of abutting panels disposed edge to edge, each of the said panels having its edge formed into an extension extending laterally from the rear face of the panels, a plurality of beams upon which the said panels are supported, the said extension being adapted to co-operate with the extension of the adjoining panels to form a pocket, one of the said supporting beams being disposed in the pocket to which the edges of the panels are adapted to be fastened, and means for fastening the abutting edges of the panels to the beam in the pocket.
16. In a molding construction, a molding panel including a base section provided with shoe portions having annular flanges, means for reinforcing the same comprising a detachable stiffener consisting of one member adapted to bear against the rear face of the panel normally under compression, and a tension truss associated with the said member for placing it under compression, and members secured to each end of the stiffener and having laterally projecting flanges bearing against the flanges of the shoe portions for resisting twisting and displacement of the stiffener with respect to the panels.
17. In a molding construction, a molding

panel, a stiffener associated with the rear face thereof, a shoe construction associated with each end of the molding panel, and members projecting laterally from the ends of the 5 stiffener at the back thereof adapted to set in the corresponding shoes for resisting twisting and distortion of the stiffening member, the pressure exerted upon the said stiffener by the said panel being transmitted to the shoe 10 constructions positioned at the ends of the stiffener.

18. In a molding construction, a molding panel, a stiffener associated with the rear face of said panel, a reenforcing shoe projecting from each end of the panel and provided 15 at its outer end with an inwardly projecting flange, and means associated with each end of the stiffener and bearing upon said flange of the corresponding shoe to transmit the 20 stresses to the said shoes, said stiffener comprising a truss construction adapted to receive the stresses transmitted from the panel and to transfer the said stresses to the said shoes.

19. In a molding construction, a plurality of molding panels positioned edge to edge, each of the said panels having a hook-like portion associated with its edge, the hook-like portions of the adjacent panels serving 30 to form a pocket, a stiffening element positioned in the pocket and overlapping the edges of the adjacent panels, and a clamping device for connecting the hook-like portions to force them outwardly from the panels and 35 for urging the stiffening element inwardly towards the panels, said device comprising a pair of clamping arms for engaging said hook portions, and a lost motion connection between the said arms.

20. In a molding construction, a plurality of molding panels positioned edge to edge, each of the said panels having a hook-like portion associated with its edge, the hook-like portions of the adjacent panels serving 45 to form a pocket, a stiffening element positioned in the pocket and overlapping the edges of the adjacent panels, and a clamping device for connecting the hook-like portions to force them outwardly from the panels and 50 for urging the stiffening element inwardly towards the panels, said device comprising a pair of clamping arms for engaging said hook portions, a lost motion connection between the said arms, and wedging mechanism 55 for urging the arms towards each other and for urging the arms outwardly away from the stiffening element, as well as for urging the stiffening element in toward the said panels.

21. In a molding construction, a plurality of molding panels positioned edge to edge, each of the said panels having a hook-like portion associated with its edge, the hook-like portions of the adjacent panels serving to 60 form a pocket, a stiffening element positioned

in the pocket and overlapping the edges of the adjacent panels, and a clamping device for connecting the hook-like portions to force them outwardly from the panels and for urging the stiffening element inwardly towards 70 the panels, said device comprising a pair of clamping arms for engaging the said hook-like portions, a lost motion connection between the said arms, a wedge extending through the arms for at all times urging the arms towards each other, and a wedge positioned intermediate the arms and the stiffening element for urging the stiffening element towards the panels and for urging the arms 75 outwardly away from the panels.

22. In a molding construction, a plurality of molding panels positioned edge to edge, each of the said panels having a hook-like portion associated with this edge, the hook-like portions of the adjacent panels serving 80 to form a pocket, a stiffening element positioned in the pocket and overlapping the edges of the adjacent panels, and a clamping device for connecting the hook-like portions to force them outwardly from the panels and 85 for urging the stiffening element inwardly towards the panels, said device comprising a pair of clamping arms for engaging the said hook-like portions, and an element having a lost motion connection with the said arms 90 and being equipped with a guiding portion for co-operating with the stiffening element in controlling the position of the clamp.

23. In a molding construction, a plurality of molding panels positioned edge to edge, each of the said panels having a hook-like portion associated with this edge, the hook-like portions of the adjacent panels serving to 100 form a pocket, a stiffening element positioned in the pocket and overlapping the edges of the adjacent panels, and a clamping device for connecting the hook-like portions to force them outwardly from the panels and for urging the stiffening element inwardly towards 105 the panels, said device comprising a pair of clamping arms for engaging the said hook-like portions, a guide element having a lost motion connection with the said arms and being equipped with a guiding portion for co-operating with the stiffening element in controlling the position of the clamp, and a wedge extending through the said guide element 110 for urging the stiffening element inwardly towards the panel and for urging the guide element and the clamping arms outwardly away from the panel.

24. In a molding construction, a molding panel comprising a sheet of metallic material having an edge thereof bent back upon itself, said edge having a groove extending therethrough and a plurality of passages extending therethrough at right angles to the groove, and a band extending through a passage thereof for tying the panel to a second panel spaced therefrom, said band having a 125 130

- tongue adapted to fit in the groove in the edge of the said panel.
25. In a molding construction, a pair of spaced molding panels, each of the said panels having an irregularly formed edge, means for tying the panels together comprising a band of material adapted to lie across the said irregularly formed edges, and means for clamping the band to the irregularly formed edges, 5 said clamping means exerting downward pressure on the band to cause the band to fit tightly the irregularly formed edges of the panels, the said irregularly formed edges serving to prevent lateral displacement of the band.
26. In a molding construction, a pair of spaced molding panels, means for tying the panels together comprising a band of material adapted to be laid between the edges of 10 the panels and a wedge member driven through the edge of one panel and passing through perforation in said band, the said wedge member bearing against the rear face of the other panel for tying the panels to 20 another wall panel spaced therefrom, locking the panels against movement toward or away from each other.
27. In a molding construction, a pair of molding elements, means for clamping the 25 elements together comprising a pair of spaced clamping jaws, one for each molding element, a pivotal connection between the clamping jaws, a wedge for drawing the clamping jaws towards each other to tightly lock the molding elements in position, and means including an irregular surface associated with one of the clamping jaws for co-operating with an edge of the wedge for preventing displacement of the same.
28. In a molding construction, a pair of associated molding elements, a stiffening member for one of the said elements adapted to be associated with the rear face of the element to strengthen the same, the other molding element being provided with a shoe for receiving an end of the stiffening element, and means associated with an end of the stiffening element adapted to be set in the shoe to co-operate with the shoe and to prevent twisting 45 of the stiffening element, the said stiffening element transmitting any forces which may be imposed on its associated molding element to the shoe.
29. In a molding construction, a molding 50 panel, top and bottom molds associated with the said panel, each of the said molds being provided with a shoe, a stiffening element for the panel having its ends disposed in the shoes of the top and bottom molds, means associated 55 with each end of the stiffening element and the corresponding shoe for preventing twisting of the stiffening element, a molding construction spaced from the molding panel, and means including a plurality of bands for connecting the shoes to the said molding con-
- struction to transmit the stresses imposed upon the stiffening element to the said molding construction.
30. In a molding construction, a pair of spaced molding panels, a mold element positioned on one of the molding panels, a tie band extending across the panels having an end extending intermediate the mold element and the associated molding panel, the said end of the tie band being provided with an aperture, a member projecting from the mold element and having an aperture aligned with the aperture of the band, and a wedge positioned in the said apertures for tying the band to the mold element, the said wedge bearing against the rear face of the associated molding panel, the panel and the band and the member of the mold element having interlocking means holding the same against relative movement.
31. In a molding construction, a cornice mold consisting of an arcuate shaped portion and a relatively straight portion integral therewith, said straight portion having a longitudinal groove and a plurality of slots, the said straight portion having an edge formed into a lateral extension to form a shoe, said arcuate shaped portion having an edge turned back upon itself to form a longitudinal pocket.
32. In a molding construction, a molding panel, a cornice member associated with an end thereof, said cornice member being provided with a shoe, a stiffener associated with the rear face of the panel having an end disposed in the said shoe, and means associated with the said end of the stiffener adapted to be set in the said shoe to transmit the stresses imposed upon the stiffener through the shoe to the cornice member.
33. In a molding construction, a molding panel, a stiffener therefor, means associated with one end of the stiffener for maintaining it in position, and resilient means associated with the stiffener intermediate its ends for drawing it towards the panel during the time the other end of the stiffener is being mounted in a predetermined position.
34. In a molding construction, a pair of spaced molding panels, a stiffener associated with each of the said panels, a shoe-like member associated with an end of each of the panels in which an end of the associated stiffener is supported, said stiffener having a laterally projecting member forming an abutment, and said shoe member having a shoulder adapted to engage the said abutment to resist displacement of the stiffener, and means including a tie band for connecting the shoe member associated with one panel to the shoe member associated with the other panel to resist the spreading apart of the panels, said band having a lateral extension adapted to fit over the abutment of

one of the stiffeners to maintain the said stiffener in engagement with the shoulder on the associated shoe member.

35. In a molding construction, a pair of spaced molding walls, each comprising a pair of molding panels positioned one upon another, stiffeners associated with the rear faces of the panels, a tie band extending intermediate the panels for tying the walls together, and a member associated with each wall extending transversely to the stiffener and to which the corresponding end of the band is fastened.

10 36. In a molding construction, a molding panel comprising a molding surface consisting of a sheet of metallic material, a plurality of slats associated with the rear of the panel for reenforcing the sheet, said sheet having portions turned back over itself to form pockets for receiving the ends of the 20 slats to maintain them in position, said turned back portions having lateral extensions spaced from the edges of the panel.

25 37. In a molding construction, a pair of spaced molding panels, a stiffener associated with the rear face of each panel, a shoe member associated with each end of the stiffener in which the end of the stiffener is adapted to be set, the shoe member having a shoulder at its outer edge and the stiffener having an 30 abutment bearing against the shoulder and connecting the said end of the stiffener with the shoe member to cause the stresses imposed on the stiffener to be transmitted to the shoe member, and means for tying the 35 shoe member associated with one end of the stiffener of one panel to the corresponding shoe member associated with the stiffener of the other panel.

40 38. In a molding construction, a pair of spaced molding panels, a stiffener associated with the rear face of each panel, a shoe member associated with each end of the stiffener in which the end of the stiffener is adapted to be set, means connecting the said end of the 45 stiffener with the shoe member to cause the stresses imposed on the stiffener to be transmitted to the shoe member, means for tying the shoe member associated with one end of the stiffener of one panel to the corresponding shoe member associated with the stiffener of the other panel, said means comprising a band of material extending from one panel to the other, said band of material 50 having one end formed into a lateral extension for engaging the associated shoe member to resist the spreading apart of the panels, and an adjustable device associated with the other end of the band adapted to engage the shoe member associated therewith.

In witness whereof, I hereunto subscribe my name this 2d day of April, 1926.
